UNITED STATES PATENT OFFICE.

VENUS H. CLARK, OF ALLIANCE, NEBRASKA.

COMBINED NOZZLE AND DEFLECTING RING.

Application filed November 16, 1923. Serial No. 675,187.

To all whom it may concern:

Be it known that I, VENUS H. CLARK, a citizen of the United States, residing at Alliance, in the county of Box Butte and State of Nebraska, have invented certain new and useful Improvements in Combined Nozzles and Deflecting Rings, of which the following is a specification.

This invention relates to a new and improved combined nozzle and deflecting ring for the watering system of railway equipment.

The principal object of the invention is to provide a device of the above character adapted to be detachably carried by the valve of a watering hose and which comprises a tapered nozzle for insertion into the opening of a tank and to secure a substantially tight fit against the walls of the opening and a new and novel deflecting ring or shield adjacent the nozzle to cause any water that might escape the opening of the tank, to be deflected back against the same.

It is well known in refilling air pressure water tanks that when the entrance port is open, the escaping air carries considerable water with it, in many instances throwing the same a considerable distance along the sides of the cars. This also happens after the water hose has been inserted into the tank and while it is being filled. In my invention, the nozzle is of tapered construction so as to fit snugly against the walls of the entrance port of the tank and, as above pointed out, I also provide a shield behind the nozzle to deflect any escaping water back under or against the cars.

Various other advantages and objects of my invention will become apparent during the continuance of the following description.

In the drawings—

Figure 1 is a view in longitudinal section taken through the body of my invention, the main pipe being shown in elevation and slightly broken away. In this view the device is also shown in association with the entrance port of the tank although this illustration does not, in any way, limit the scope of the invention.

Figure 2 is a view in cross elevation showing my invention in its preferred embodiment.

In describing the invention in detail, 10 indicates the body of the nozzle which is in the form of a pipe open at both ends, one end being exteriorly threaded as at 11 for the purpose that will presently appear. A cone 12 is mounted on the forward end of pipe 10 and has the forward or smaller end terminating just short of the adjacent end 60 of the pipe while its rear or larger end terminates just beyond the intermediate portion of the pipe. The cone is preferably constructed of rubber, although any other suitable or desirable material may be used. 65

The shield consists of a body portion of substantially the same diameter as the main deflecting portion. The intermediate portion of the outer wall of the body portion of the shield is also cut away and curved as 70 at 15 so that the inner wall of the entire shield will present a smoothly curved surface to whatever it is directed to or against. It will be noted that by reason of the peculiar curvature of the flange 14 of the shield 75 that water directed there against will be deflected back in the substantial direction from which it came.

In Figure 1, I have shown a part of a tank 16 provided with an opening 17 and have shown the nozzle portion of my invention arranged therein as in actual practice. It will be readily seen that if any water escapes through the opening 17 it will be directed against the inner curved surface of 85 flange 14 of the shield, and directed back against the tank.

Removably mounted on pipe 10, inwardly of the threads 11 and immediately adjacent the rear end of the rubber cone 12, is the 90 shield or deflecting ring of the invention. This shield or ring, which is preferably of metal, consists of a bell-shaped member presenting a raised central supporting portion 13 and a circular deflecting flange 14; the central portion extending almost flush with the outer edge of the flange and being cut away and curved as shown at 15 so that the inner face of the shield will present a smoothly curved surface by which any water impinging thereon will be deflected back substantially in the direction from whence it came. It will be observed, moreover, that the peculiar shape of the shield on the de-

flecting side, with the half-circle effect in the center, causes it to drain at all times to the bottom.

In the usual watering system of railway equipment it is customary to supply the toilets and lavatories of a railway car with water from a supply tank 16 located under the car and provided with an entrance port 17 for purposes of refilling. The water in the tank is subjected to a ten-pound air pressure so as to be raised to the proper level and is fed into the lavatory and toilet supply pipe through an outlet pipe from the tank. The tank is further equipped with a three-way valve operating with one movement of the lever to shut off the air pressure while at the same time opening the entrance port 17 and the waste pipe or drain of the tank. It is necessary to refill these tanks at frequent intervals as the supply carried at one time is inadequate for the passengers' requirements and, as a rule, they are refilled at each division point on the railroad. Under present conditions, the refilling operation is carried out with a great degree of annoyance and physical discomfort both on the part of passengers and the trainmen assigned to the task of refilling the tanks. This is due to the fact that when the entrance port 17 is opened by the manipulation of the three-way valve as previously described, the air pressure released through the waste pipe and entrance port carries with it considerable water which it sometimes throws to a distance from eight to ten feet across the platform where the passengers are entering and leaving the trains, causing them to get wet, and, in addition, making the platform slippery and disagreeable to walk on, especially in winter when it collects and freezes. The same disadvantages are present, also, when refilling the gravity or overhead tanks which supply the drinking water. These tanks are each filled through a pipe leading from the outside of the car to the top of the tank; the outside end of the pipe being provided with an entrance port through which the water is injected.

At present, the tanks are filled by means of an ordinary rubber hose leading from a water line and having a stopcock or valve connected to the outer end. This stopcock has a short length of $\frac{3}{4}$ inch pipe screwed into it to serve as a nozzle but since the entrance ports vary in size from $1\frac{1}{4}$ inches to 2 inches in diameter, there is always considerable loss of water when refilling the tanks, in addition to what is released by the escaping air pressure.

In adapting the invention to present-used equipment, the $\frac{3}{4}$ inch pipe above referred to is replaced by my combined nozzle and deflecting ring which is screwed into the stopcock by means of the threads 11 on pipe 10. The tapered formation of the rubber cone 12

enables the device to snugly fit various sizes of entrance ports and when pressed firmly in the entrance port of the air-pressure tank 16 it diverts the escaping air and water through the waste pipe so that it discharges under the car. Any water or air that escapes past the cone during the insertion of the nozzle into the port will strike the shield or ring 13 and be deflected back against and under the car. Also, in refilling the gravity tanks, the nozzle is inserted firmly in the entrance port of the filling pipe, making a tight joint so as to accumulate pressure enough to force the water to the top of the tank; the rubber cone serving as a gasket 80 and the shield as a deflecting ring for deflecting under the car any water that may escape through the port.

When the device is attached to the rubber hose, as aforementioned, the shield serves 85 also as a guard for supporting the end of the nozzle out of contact with the ground, or mud, or whatever it happens to fall on when the hose is released, thus conforming to the requirements of the different State 90 health and sanitary boards.

What is claimed is:

1. A combined nozzle and deflecting ring for refilling a supply tank of the watering system of railway equipment, consisting of 95 a pipe exteriorly threaded at one end, a rubber cone mounted on the said pipe with its larger end terminating inwardly of the threaded end of the pipe, and a deflecting ring mounted on the pipe in the space between the threaded end thereof and the larger end of the said cone.

2. A combined nozzle and deflecting ring for refilling a supply tank of the watering system of railway equipment, consisting of 105 a bell-shaped member having a central opening, a rubber cone projecting centrally of one side of the said bell-shaped member and having a central passage in alignment with the said central opening of the bell-shaped 110 member, and means on the opposite side of the bell-shaped member for connecting it with a water-supply source.

3. A combined nozzle and deflecting ring for refilling a supply tank of the watering 115 system of railway equipment, consisting of a rubber cone tapered to fit an opening in the tank, a bell-shaped member presenting a raised central portion in abutment with the large end of the said tapered cone, said cone and bell-shaped member having aligned 120 openings co-operating to provide a central passage therethrough, and a pipe within the said passage and supporting the said tapered cone and the said bell-shaped member thereon, said pipe having a screw-threaded portion exposed beyond the bell-shaped member.

4. A combined nozzle and deflecting ring consisting of a tubular member having means 130

of attachment to a source of water-supply, a bell-shaped member mounted thereon adjacent one end and presenting a circular deflecting flange and a raised central portion 5 extending almost flush with the outer edge of the said flange, said flange and said central portion having curved deflecting surfaces causing the said bell-shaped member

to drain to the bottom, and a rubber cone covering the said pipe in advance of the said bell-shaped member and having its larger end in abutment with and corresponding in size to the said raised central portion of the said bell-shaped member. 10

In testimony whereof I affix my signature.

VENUS H. CLARK.
